UNITED STATES PATENT OFFICE.

PETER B. JOHNSON, OF SEATTLE, WASHINGTON.

HYDROCARBON-BURNER.

1,381,560.

Specification of Letters Patent. Patented June 14, 1921.

Application filed June 12, 1920. Serial No. 388,661.

To all whom it may concern:

Be it known that I, PETER B. JOHNSON, a citizen of the United States, residing at Seattle, in the county of King and State of Washington, have invented a certain new and useful Improvement in Hydrocarbon-Burners, of which the following is a specification.

My invention relates to improvements in hydrocarbon burners and to improvements in thermostatic means for controlling the supply of fuel to such burners and the object of my invention is to provide a simple and efficient burner that is adapted to burn kerosene, crude oil or other crude petroleum products.

Another object is to provide a burner embodying a thermostatic control by which the fuel supply is automatically shut off when the burner becomes cold thereby eliminating the danger of flooding the burner with fuel with the consequent possibility of explosion and fire.

A further object is to provide a burner in which the flame from the side burner elements is directed outwardly and upwardly in such a manner as to prevent the main body or casing of the burner from becoming intensely hot thereby tending to eliminate all possibility of back fire within the said burner casing.

A still further object is to provide a burner having an expansion chamber for the reception of the gas after it is generated the said expansion chamber having a plurality of separably controlled burner elements for the outlet of the gas.

A still further object is to provide a burner embodying novel means for cleaning the gas outlet aperture formed in the gas generating element of the burner.

A still further object is to provide a burner embodying simplicity, durability and economy in construction, that may be readily dismantled for removal and renewal of parts; that is positive and efficient in operation and that will not readily get out of order.

With the above and other objects in view, which will be apparent as my description proceeds my invention consists in the novel construction, adaptation and combination of parts of a hydrocarbon burner as will be more clearly hereinafter described and claimed.

In the accompanying drawing Figure 1, is

a plan view looking down on the top of a burner constructed in accordance with my invention,

Fig. 2, is a view in side elevation of the same,

Fig. 3, is a view in end elevation of the same, and

Fig. 4, is a view in cross section substantially on a broken line 4—4 of Fig. 2. 65

Like reference numerals designate like parts throughout the several views.

Referring to the drawings, the numeral 5 designates the base of the burner casing which base 5 is provided with end plates 6 70 and 7 and with side plates 8 and 9, the said end plates and side plates being integral with the base 5 or otherwise rigidly secured thereto in such a manner as to form a substantially rectangular expansion chamber 10. 75

Extending lengthwise between the end plates 6 and 7 in substantially the same plane as the top edge of the side plates 8 and 9, is a trough like receptacle or priming pan 11, within which is disposed non-combustible absorbent material as indicated at 12, the said priming pan being adapted to receive liquid fuel which is lighted for the purpose of heating up the burner.

Extending lengthwise of the burner on opposite sides of the priming pan 11 are two perforated plates 13 and 14 that are preferably slidable in grooves 15 in the priming pan 11 and side walls 8 and 9 respectively as shown in Fig. 4, and that constitute removable burner elements through which gas may be emitted from the expansion chamber 10. 85

Other burner elements are formed by angularly disposed perforated burner plates 16 and 17 that are secured to the side walls 95 8 and 9 and rest upon the upwardly projecting outer edges 18 of the base 5 in such a manner as to form fuel chambers 20 and 21 of triangular cross sectional shape from which gas may be emitted through the perforated burner plates 16 and 17. 100

The fuel chambers 20 and 21 communicate with the expansion chamber 10 through openings 22 in the side walls 8 and 9 which openings 22 are adapted to be closed by sliding doors 23 that are arranged to be moved by rods 24 that project outwardly through packing boxes 25 in the end of the burner casing. The doors 23 form an easily operated means for shutting off the feed of fuel to the chambers 20 and 21 or for regulating 110 such feed of fuel to regulate the heat of the

flame from the side burner plates 16 and 17 independently of the top burner plates 13 and 14. The side burner plates 16 and 17 are arranged at an angle of substantially 5 forty-five degrees so that they will direct the gas away from the sides of the burner casing and prevent such burner casing from becoming intensely hot thereby obviating the danger of explosion within the expansion 10 chamber 10.

Fuel for the burner is gasified by passing it through a U shaped coil 26 having a downwardly bent inlet end 27 and a downwardly bent outlet end 28 at the front end of the 15 burner. The coil 26 is supported above the top of the burner and in symmetrical relation with respect to such burner by two brackets 30, 31, that are secured to the end 7 of the burner housing and one bracket 32 20 that is secured to the end 6 of the burner housing, the coil being secured to the several brackets by set screws 33 in such a manner that it may be easily and quickly removed.

The inlet end 27 of the vaporizing coil 25 is connected by an elbow fitting 34 with a valve 35 which valve is provided with a tubular shank 36 that may be connected with a fuel inlet pipe, not shown, through which liquid fuel under pressure may be introduced. 30

The outlet end 28 of the vaporizing coil is provided with a perforation 37 through 35 which gas may be emitted and such outlet end extends for a considerable distance below the perforation 37 to form a sediment trap having a screw cap 38 that may be removed to permit such sediment trap to be cleaned out.

The outlet end 28 of the vaporizing coil is 40 provided at a point directly opposite the perforation 37 with a boss 40 that is connected with a packing box 41 through which is threaded a pointed stem 42 that may be screwed inwardly to cause the point thereof 45 to project through the perforation 37 and clean the same out in case such perforation becomes clogged.

The gas outlet perforation 37 is arranged 50 to direct a jet of gas centrally into the end of a tubular conduit 43, which I term a Bunsen tube, and which extends into the expansion chamber 10 to a point about midway between the two ends of the burner and has an upwardly curved wall 44 at its inner end that 55 closes the bottom half of such tube as is more clearly shown in Figs. 2 and 4, and tends to direct gasified fuel that is emitted from such tube upwardly. The tube 43 is open at the outer end so that if any liquid fuel is accidentally introduced into such tube it will 60 drain off quickly and will not enter the expansion chamber 10.

The valve 35 that controls the inlet of fuel is arranged to be opened and closed 65 by the turning of a valve stem 45 that is

provided on its outer end with a lever arm 46 which is adjustably secured thereto by a set screw 47. The upper end of the lever arm 46 is bifurcated and is provided with a cross pin 48 over which the forked end of 70 an actuating arm 50 is arranged to fit.

The actuating arm 50 is fulcrumed on brackets 51 that are integral with or rigidly secured to an upwardly projecting portion of the end wall 7 and the upper end 52 of 75 such arm is arranged to project through an opening in one end of a bar 53 of thermostatic metal that rests upon the end wall 7 and extends lengthwise in the medial plane of the burner and the other end of which is 80 rigidly secured to the end 6 of the burner casing. The thermostatic bar 53 is preferably of hexagonal cross section throughout the greater portion of its length but may be flattened at its two ends substantially as shown in Fig. 2. When the thermostatic bar is hot it will elongate and by reason of its connection with the actuating bar 50 will open the valve 35 thus permitting fuel to flow to the burner. When 85 the thermostatic bar cools off it will contract in length and will move the actuating bar to close the valve 35 thus shutting off the supply of fuel and preventing flooding of the burner in case the flame of such 90 burner is accidentally extinguished.

When the burner is to be lighted liquid fuel is poured into the priming trough 11 and ignited and allowed to burn to heat the vaporizing coil 26 and thermostatic bar 53 100 thus causing the bar 53 to elongate and open the valve 35 thereby admitting liquid fuel to the coil 26 which has already been heated so that as the liquid fuel moves toward the discharge end of such coil it will be vaporized and thoroughly gasified and will be emitted from the perforation 37 under pressure in the form of a jet of gas that is directed inwardly through the conduit 43 and will tend to draw air inwardly along with it. 105

The gas passes from the tube 43 into the chamber 10 where it has an opportunity to expand and mix more thoroughly with the air that also enters through the tube 43 before it is emitted from the perforations in 110 the burner plates and burns.

When the burner is working properly the pressure of the gas within the expansion chamber 10 will be slightly in excess of atmospheric pressure and the gas that is 115 emitted from the perforation in the plates 13, 14, 16 and 17 will burn with a clean, hot, blue flame.

The heat of the burner may be regulated by regulating the supply of fuel to such 120 burner and the flame from the side burners 16 and 17 may be regulated or entirely shut off by adjustment of the gates or doors 23.

From the foregoing description taken in connection with the accompanying drawings 130

the form of construction and method of operation of my oil burner will be readily understood but, while I have described the principle of operation of the invention together with the device which I now consider to be the best embodiment thereof it will be understood that the device shown is merely illustrative and that such changes in the construction thereof may be resorted to as are within the scope of the following claims.

What I claim is:

1. An oil burner comprising a relatively long rectangular base, end walls projecting upwardly from said base, side walls projecting upwardly from said base, said base extending outwardly beyond said side walls, a priming pan extending lengthwise between said two end walls centrally of said burner, a horizontal perforated burner plate disposed on each side of said priming pan said burner plates and said priming pan constituting the top wall of said burner, angularly disposed perforated side burner plates extending from the edges of said base to said side walls and forming fuel chambers of triangular cross sectional shape, the said side walls having openings for the admission of fuel to said chambers, doors for said openings, means extending to the exterior of the burner for opening and closing said doors, a tubular conduit projecting into the interior of said burner and a vaporizing coil disposed above the burner body and having a downwardly projecting end provided with a gas outlet perforation for directing a jet of fuel gas into said tubular conduit.

2. An oil burner comprising a relatively long rectangular base, end walls projecting upwardly from said base, side walls projecting upwardly from said base, a priming trough extending lengthwise between said end walls medially of said burner, a removable perforated burner plate disposed on each side of said priming trough, said burner plates and said priming trough constituting the top wall of said burner, a U shaped vaporizing coil supported above the burner plates, a tubular conduit projecting into one end of said burner, and a downturned end on said vaporizing coil, said downturned end having a perforation therein that is arranged to deliver a jet of gas into said tubular conduit.

3. An oil burner comprising a relatively long rectangular base, end walls projecting upwardly from said base, side walls projecting upwardly from said base, a priming trough extending lengthwise between said end wall medially of said burner, a removable perforated burner plate disposed on each side of said priming trough, said burner plates and said priming trough constituting the top wall of said burner, a U shaped fuel

vaporizing coil supported above said burner plates, a tubular conduit projecting into one end of said burner, a downturned end on said vaporizing coil, said downturned end having a perforation formed therein that is arranged to deliver a jet of gas into said tubular conduit, a valve controlling the inlet of liquid fuel to the said U shaped fuel vaporizing coil, and thermostatic means disposed within the area heated by said burner for opening said valve when said burner is lighted and closing said valve when said burner is extinguished.

4. An oil burner comprising a relatively long rectangular base, end walls projecting upwardly from said base, side walls projecting upwardly from said base, a priming trough extending lengthwise between said end walls medially of said burner, a removable perforated burner plate disposed on each side of said priming trough, said burner plates and said priming trough constituting the top wall of said burner, a U shaped fuel vaporizing coil supported above said burner plates, a tubular conduit projecting into one end of said burner, a downturned end on said vaporizing coil, said downturned end having a perforation formed therein that is arranged to deliver a jet of gas into said tubular conduit, a valve controlling the inlet of liquid fuel to the said U shaped fuel vaporizing coil, a thermostatic bar arranged to receive the heat from said burner, means on said burner adapted to rigidly support one end of said bar, and actuating means interposed between the other end of said bar and said valve for opening said valve in response to the elongation of said bar and closing said valve in response to shortening of said bar.

5. An oil burner comprising a relatively long rectangular base, end walls projecting upwardly from said base, side walls projecting upwardly from said base, a priming trough extending lengthwise between said end walls medially of said burner, a removable perforated burner plate disposed on each side of said priming trough, said burner plates and said priming trough constituting the top wall of said burner, a U shaped fuel vaporizing coil supported above the burner plates, a tubular conduit projecting into one end of said burner, a downturned end on said vaporizing coil, said downturned end having a perforation formed therein that is arranged to deliver a jet of gas into said tubular conduit, a valve controlling the inlet of liquid fuel to the said U shaped fuel vaporizing coil, a stem on said valve, a lever arm adjustably secured to said stem, a pivotally mounted actuating bar arranged to engage with said lever arm for opening and closing said valve, and a thermostatic bar extending lengthwise of said burner body and above the said U shaped fuel vaporiz-

- ing coil, said thermostatic bar having one end rigidly supported by said burner body and the other end connected with said actuating bar.
- 5 6. An oil burner comprising a relatively long rectangular base, end walls projecting upwardly from said base, side walls projecting upwardly from said base, said base extending outwardly beyond said side walls, a 10 priming trough extending lengthwise between said end walls medially of said burner, a horizontally disposed and removable perforated burner plate disposed on each side of said priming trough, said burner 15 plates and said priming trough constituting the top wall of said burner, angularly disposed and removable perforated side burner plates extending from the edges of said base to said side walls and forming fuel chambers of triangular cross sectional shape, said side walls having openings for the admission of fuel to said chambers, doors for said openings, means extending to the exterior of the burner for 20 opening and closing said doors, a U shaped fuel vaporizing coil supported above said horizontally disposed burner plates, a tubular conduit projecting into one end of said burner, a downturned end on said vaporizing coil, said downturned end having a perforation formed therein that is arranged to deliver a jet of gas into said tubular conduit, a valve controlling the inlet of liquid fuel to said U shaped fuel vaporizing coil, a stem on said valve, a lever arm adjustably secured to said stem, a pivotally mounted actuating bar arranged to engage with said lever arm for opening and closing said valve, and a thermostatic bar extending lengthwise of said burner body and above the said U 30 shaped fuel vaporizing coil said thermostatic bar having one end rigidly supported by said burner body and the other end connected with said actuating bar.
- 35 In witness whereof, I hereunto subscribe my name this 5th day of June, A. D. 1920.
- 40
- PETER B. JOHNSON.
